UNITED STATES PATENT OFFICE.

GEORGE HENRY MOEBS, OF PARRAMATTA, NEAR SYDNEY, NEW SOUTH WALES,
AUSTRALIA.

CASEMENT AND TRANSOM STAY AND SASH AND DOOR HOLDER.

Application filed August 7, 1922. Serial No. 580,352.

To all whom it may concern:

Be it known that I, GEORGE HENRY MOEBS, subject of the King of Great Britain and Ireland, residing at 109 Argyle Street, Parramatta, near Sydney, New South Wales, Australia, have invented certain new and useful Improvements in Casement and Transom Stays and Sash and Door Holders, of which the following is a specification.

- 10 This invention relates to stays or holders for hinged doors and casement sashes, for staying or holding the same frictionally in any position in which they may have been adjusted so that they will remain in such 15 position notwithstanding vibration and wind pressure though movable by the application of a degree of manual force proportioned to overcome the frictional adjustment of the device.
- 20 The fitting in which the invention consists is usable in connection with slidable sashes and reversibly hung sashes as well as in connection with hinged sashes, and transoms; but it is appropriately fixed in each case 25 having regard to the service required.

The fitting comprises a friction rail with terminal mounting lugs, adapted for mounting it on a sash or door or on its frame, a slider sleeve with cork insert forming a 30 collar shoe to run on said rail frictionally, an adjusting screw attachment for varying the compression of the cork shoe, and a link or stay bar pivotally fixed to a butt plate or to an offset butt bracket, which butt is adapt- 35 ed to be fixed to a sash or door or to its frame according to the particular arrangement of the device adopted in each case.

In the accompanying drawings:—

Fig. 1 is a perspective view shewing the 40 fitting used as a casement sash stay with the stay bar pivotally centered on a stud plate fixed to the frame sill;

Fig. 2 is a fragmentary horizontal section corresponding with Fig. 1, with the sash 45 shewn in closed position;

Fig. 3 is a sectional plan indicating the movement and relative position of the parts when the sash (Fig. 1) is in partly open position;

50 Fig. 4 is a top plan view shewing the fitting of the device externally to a casement sash using a butt bracket for the pivotal support of the link, the sash being shown closed in this figure;

Fig. 5 is an elevational view corresponding with Fig. 4;

Fig. 6 is a plan view corresponding with Fig. 4 but shewing the sash in open position; and

Fig. 7 is a fragmentary sectional elevational view shewing the attachment for adjusting the pressure of the cork friction shoe on the rail.

It is to be understood that the device may be fitted to a door or window, either on the 65 top rail, mid-rail or bottom rail position according to the necessities of each case; furthermore that it may be used in connection with up-swinging or down-swinging transoms to hold the sash in any partly open 70 position to which it may be brought by manual adjustment. The fitting for transoms will be understood if the drawings be read sideways instead of erect as applying to such sashes. For carrying vertically sliding 75 sashes, as for instance in railway carriages, so as to avoid the necessity for fitting counterbalance weights, the rail may be fixed on the head of the frame and the pivotal mounting for the link end on the top 80 rail of the sash. In this case the slider which works on the rail may be provided with a hand grip to facilitate the moving of it along the rail to allow of the sash being raised or lowered readily. If the length of 85 the link be appropriately proportioned so that when the sash is fully closed down the link sets erect or nearly so, the link will then serve as a lock to prevent the forcing up of the sash from a position outside the 90 apartment in which the sash is fitted. It will be understood that for vertical sash mounting according to this method two of the fittings may be used to support the sash from two points at either side of it instead 95 of from one central point only on its top rail, thereby to obtain better security and better balance.

Referring to Figs. 1 to 3:

A is the friction rail, B lugs on the end 100 of it adapted for mounting it on a door, sash, or frame, C the slider, D cork inserts in the slider C, E link, K pivot connection of link E to slider C, F pivot connection of link E to butt plate G. The plate G is 105 adapted to be fixed by screws H.

The slider C may be provided with a screw adjustment (see Fig. 7) for varying

the pressure on the cork insert D and thus varying the frictional resistance to movement of the slider C on the rail A.

Referring to Figs. 4 to 7:—

- 5 The rail A, which is preferably a rod of circular section, is mounted in end bracket lugs B—B which are screwed to the sash or door P to hold the rail A horizontally thereon. C is a tubular sleeve adapted to slide 10 along the rail A. D is a cork sleeve or shoe contained in a cavity in the sleeve C, with a metal back plate E behind it, and F is a tensioning screw by which the bearing pressure on the cork shoe D may be adjusted. 15 It is preferred that a cork tubular sleeve should be used rather than a shoe in order to obtain a cork-to-metal grip on the top side as well as on the underside of the bar. The stem piece G of the sleeve C is rotatably 20 mounted in one end of the stay link H; the screw F is tapped up through this stem piece. The other end of the stay link H is pivotally mounted at K in the end of a bracket L, the butt M of which is screwed 25 to the frame post N on which the door or sash P is hung by hinges O. The bracket L is set back angularly to allow the sash or door to be swung open on its hinges past the right-angle position.

- 30 In the closed position (Fig. 4) the sleeve

C locates near one end of the rail A. As the sash or door P is opened, the sleeve C slides along said rail A towards its other end as seen in Fig. 3. The retardation effect on the swinging movement of the sash or door 35 is controllable according to the degree of tension applied to the cork shoe D by the adjusting screw F.

What I claim as my invention and desire to secure by Letters Patent is:—

A sash or door holder including a rail provided with means for fixing the same to a sash or door, an annular casing surrounding said rail and slidably along the same, said casing being provided at its opposite 45 ends with inwardly extending flanges, a sleeve of friction material arranged in said casing and frictionally engaging said rail, said flanges preventing axial movement of the sleeve relatively to the casing, a plate 50 arranged in said casing and bearing against said sleeve, a screw engaging said casing for varying the tension of said plate, and a link pivotally connected at one end to said casing and provided at its opposite end with 55 means to facilitate its attachment to a door or window frame.

In testimony whereof I affix my signature.

GEORGE HENRY MOBBS.
